UNITED STATES PATENT OFFICE.

FRANCIS J. TORRANCE, OF ALLEGHENY, PENNSYLVANIA.

DESIGN FOR A BATH-TUB.

SPECIFICATION forming part of Design No. 19,682, dated March 4, 1890.

Application filed November 13, 1889. Serial No. 330,238. Term of patent 14 years.

To all whom it may concern:

Be it known that I, FRANCIS J. TORRANCE, a citizen of the United States, residing at Allegheny, in the county of Allegheny and State 5 of Pennsylvania, have invented a certain new Design for Bath-Tubs; and I do hereby declare the following to be a full, clear, and exact description of the invention, reference being had to the accompanying drawings, which 10 form part of this specification.

This design has relation to bath-tubs; and the design consists in a bath-tub having rounded corners and having an ornamental flange or bead around its mouth, the outer 15 surface of the walls of the tub and the exposed portion of the bead being ornamented by broken irregular lines and spaces in conventional representation of variegated marble.

20 In the accompanying drawings, the figures shown illustrate a tub embodying my design, Figure 1 being a plan, and Fig. 2 a side view.

A designates the body of the tub, B the

flange or bead around the mouth, and C the ornamental legs or supports.

Having described my invention, what I 25 claim is—

1. The design for a bath-tub, as herein shown and described, consisting of the tub having rounded corners and a flanged or 30 beaded mouth, the outer surface of the walls of the tub being ornamented by broken irregular lines and spaces in conventional representation of variegated marble.

2. In a design for a bath-tub herein shown 35 and described, the legs having their outer surfaces ornamented by broken irregular lines and spaces in conventional representation of variegated marble.

In testimony that I claim the foregoing I 40 have hereunto set my hand this 23d day of October, 1889.

FRANCIS J. TORRANCE.
